EBENEZER S. BACON, OF DETROIT, MICHIGAN, ASSIGNOR OF ONE-HALF TO JOHN S. HANLEY, OF BUFFALO, NEW YORK.

DRY-SOAP-DELIVERY APPARATUS.

1,095,542.

Specification of Letters Patent.

Patented May 5, 1914.

Application filed July 5, 1913. Serial No. 777,380.

To all whom it may concern:

Be it known that I, EBENEZER S. BACON, citizen of the United States, residing at Detroit, county of Wayne, State of Michigan, have invented a certain new and useful Improvement in Dry-Soap-Delivery Apparatus, and declare the following to be a full, clear, and exact description of the same, such as will enable others skilled in the art 10 to which it pertains to make and use the same, reference being had to the accompanying drawings, which form a part of this specification.

My invention relates to dry soap delivery 15 apparatus, in which powdered dry soap is delivered to the user by a manipulation of the apparatus, and its object is to furnish an apparatus which ordinarily delivers a measured quantity of soap when the palm of the 20 hand is pressed against the valve.

It consists in the apparatus and combinations hereinafter described and claimed.

In the drawings, Figure 1 is a vertical 25 sectional view of the apparatus with the valve closed. Fig. 2 is a vertical sectional view of the lower portion of the apparatus showing the valve open. Fig. 3 is a cross-sectional view on the line X—X of Fig. 1, showing a cross-section of the valve on that 30 line. Fig. 4 is a partial, perspective view of the interior of Fig. 1, showing the detail of the attachment of the spring which controls the valve. Fig. 5 is a perspective view of the valve shown sectionally as Figs. 1 and 2.

35 In the drawings similar letters refer to similar parts.

A is the shell or receptacle for the soap. B is a bracket to which it may be soldered or otherwise fastened, which said bracket may 40 be attached to any convenient support as C in any convenient manner. The receptacle A at this lower portion is preferably in the form of a frustum of a cone A' and terminates in a cylinder or valve casing D 45 which contains the valve E.

S is a spiral spring with the spirals so formed as to conform circumferentially to the interior of the receptacle A and its conical portion A'. It is attached to the wall of 50 the receptacle A by means of a bracket A² rigidly fastened to said wall and being perforated at a with a perforation of the proper size and curvature to receive the end s of the spring. The spring S being made of wire 55 has its end simply slid through the aperture

a after being inserted in the receptacle A, by merely turning the spring sufficiently to force the end s through such aperture. The lower end of the spring s' rests upon the head or disk portion of the valve E and 60 compels the valve to remain normally in a closed position, as shown in Fig. 1.

The valve E is of peculiar construction. It consists of a disk or head F resting upon a raised, thin ledge G formed on the inside 65 of the coned receptacle. Non-detachably joined to the disk or head F are two planes arranged at right angles in cross-section as shown at f, f in Fig. 3. The planes f, f form the valve stem. The lower end of the 70 valve is a ball F' which is non-detachably joined to the planes f, f, and thus in this manner the plate F and the ball F' are non-joined to the planes f, f, and thus in this 75 detachably joined together by means of the planes f, f. The planes f, f fit closely within the cylinder A³, which forms a continuation of the frustum of the cone A', so that the vertical movement of the valve is guided by the planes f, f, that form the stem. The cylinder A³ is shorter than the valve, including the ball F', so that the ball, when 80 the valve is closed, projects below the cylinder as shown in Fig. 1. The ball F' may be designated the push member as it operates similar to a push button.

85 In using the device the valve is opened by pressure of the user's hand against the ball, pushing the head or disk F off from its seat G and against the tension of the spring S. This distributes the powdered soap and 90 allows the amount of soap collected above the ball F', between it and the valve F, to descend to the user's hand. The apparatus ordinarily delivers a measured quantity of soap for the push member or ball will 95 ordinarily be struck by the palm of the hand. This will raise the valve and allow the soap to drop in around the valve stem, but with the valve in raised position, the palm of the hand will act as a stop to prevent the soap 100 from dropping out of the cylinder. However, when the pressure on the push member is released the valve will again close on its seat and prevent any more soap from descending. Thereupon the measured quantity 105 of soap about the valve stem will descend into the user's palm, it being free to pass around the ball or push member when the hand is removed from the orifice in the cylinder or valve casing.

A cover H is provided, preferably with a hinge H', a hasp H², and a staple H³, and thus may be secured by a padlock H⁴.

The spring S has its lowest coil resting 5 against the head of the valve while practically all of the other coils lie against the inner surface of the receptacle. When the valve is raised by the hand all of the coils are slightly shifted upward and of course 10 when the valve is dropped the coils shift again downward. This gives a scraping action which prevents the caking of the powdered soap upon the walls of the receptacle. The coil spring thereby not only 15 acts as an agitator for the mass of powdered soap, but also prevents its sticking to the sides of the receptacle.

Having thus described my invention, what I claim is:

Soap delivery apparatus, comprising a receptacle provided with rigid walls and having a delivery opening at the bottom, a valve controlling such opening and a spiral spring for normally keeping the valve closed, the said spiral spring having its coils lying 25 against the interior side surfaces of the receptacle.

In testimony whereof, I sign this specification in the presence of two witnesses:

EBENEZER S. BACON.
